Kingsbacher, Pasadena, Calif.

Application July 30, 1945, Serial No. 607,850

5 Claims. (Cl. 211—99)

1

This invention has reference to foldable or collapsible racks of the general type adapted to be mounted upon a wall and adapted to carry neckties or other similar articles of apparel. The general purpose and objective of the invention is to provide a form of rack which is extremely simple in its structure and operation, and which consists of only two pieces each capable of low cost production by molding in some suitable material such as a plastic.

The features of the invention will best be understood from the following detailed description of a preferred form, reference being had to the accompanying drawing in which,

Fig. 1 is a vertical section showing the rack in its extended position;

Fig. 2 is a vertical section taken as indicated by line 2—2 on Fig. 1;

Fig. 3 is a section similar to that of Fig. 1 but showing the rack in its collapsed or hanging position, and

Figs. 4 and 5 are diagrams illustrating the mode of assembly and disassembly of the parts.

As shown in the drawing the rack has a body B in the form of a bracket adapted to be secured by screws or otherwise to a wall or other upright surface. The body bracket B has two forwardly projecting ears 10, one at each of the opposite ends of its elongate base member 9. The hanger 20 of the rack hangs from those two ears and is adapted either to project out horizontally from the bracket as shown in Fig. 1 or to hang down vertically from it, as shown in Fig. 3. The body bracket B with its integral ears 10 constitutes one of the two moldable pieces of the device, and the hanger 20, in the form of a grid which will be explained, constitutes the other of the two pieces of the complete device.

Hanger 20 is generally rectangular in form and is comprised of an external framing and transverse grid bars 21, the framing and grid bars being integrally molded in one piece. The external framing includes a transverse member 22 which will be called the head member of the frame, two longitudinal side members 23 between which the grid bars 21 extend, and a transverse frame member 24 at the outer or lower end of the hanger. The length dimension of the hanger frame, and the number of spaced grid bars 21 may be made as desired.

The external width dimension of the hanger frame (the dimension in Fig. 2 between the outer edge faces of the two longitudinal frame members 23) is preferably somewhat less than the corresponding width dimension between the two

2

internal opposed faces of the two ears 10. Two integrally molded pins 11 project oppositely from the opposite edge faces of 23 into two horizontally extending slots or grooves 12 in the inner faces of the two ears 10. Pins 11 are located a little distance from the extreme head end of hanger 20, as shown in Fig. 1; and when the hanger is in the horizontal position of Fig. 1 the extreme head end of the head frame member 22 is received in a horizontal groove 14 which is recessed into the front face of the main member 9 of bracket body B. In this position of the parts pins 11 are located inward of the outer ends of ear slots 12, as shown in Fig. 1. In that position the weight of the hanger and of any articles upon it, is taken by pins 11 bearing downwardly on the lower walls of slots 12, and by the head end 22 bearing upwardly against the upper wall of groove 14. Those slot and groove walls are so located, with relation to head frame member 22 and pins 11 that hanger 20 will be supported in substantially horizontal position. Groove 14 is preferably a little wider in a vertical direction than head member 22, and ear slots 12 are preferably a little wider in a vertical direction than the diameters of pins 11, to give clearances which will allow the hanger to be moved between its two positions easily and without the necessity of accurate registration.

30 To lower the hanger to the vertical or collapsed position of Fig. 3, the hanger is merely pulled outwardly (to the left in Fig. 1) until head member 22 clears groove 14. This movement moves pins 11 out to or toward the outer closed ends 35 of slots 12. The hanger may then be allowed to swing downwardly to the position of Fig. 3. Conversely, to move the hanger from the position of Fig. 3 to that of Fig. 1, the hanger is first swung up to the horizontal position with pins 11 still at 40 or near the outer ends of slots 12. Upon reaching the horizontal position, hanger 20 is merely shoved horizontally inwardly to enter head member 22 in bracket groove 14.

To facilitate assembly and disassembly of the 45 rack one of the ears 10, say the left one in Fig. 2, is provided with a vertical extension slot 13 extending diagonally upwardly from the horizontal slot or groove 12 to the upper end surface of the ear 10, as shown in Fig. 1. With hanger 20 in such a horizontal position as shown in Fig. 1 and pulled outwardly to clear head member 22 from groove 14, one of pins 11 (the one shown at the left in Fig. 2) then registers with the vertical extension slot 13. However, in that position 50 the hanger cannot be removed from the bracket

because the inward inclination of slot 13 will force the head end 22 against the bracket as the hanger is moved up. To remove the hanger it is necessary first to swing it to a position which it does not normally occupy in use; it must be swung up to or close to vertical position to its hanging position of Fig. 3. In that last described position of the parts, the left hand side of hanger 20 can be swung upwardly to move the lefthand pin up through and out of slot 13. With the left hand side of the hanger swung up high enough to clear the lefthand ear 10, the righthand hanger pin 11 may then be removed from the righthand ear slot 12 by moving the hanger toward the left. The loose clearance of the latter mentioned pin 11 in its slot 12, and the lateral clearance at C between the side edges of hanger 20 and the inner opposed faces of ear 10, as shown in Fig. 2, allow of the swinging movement described. To assemble the parts the opposite sequence of operations is performed.

Both ears 10 could of course be provided with the vertical extension slot 13, and in that event the hanger 20 could merely be lifted bodily upwardly after being swung to either of its vertical positions. However the provision of the vertical slot 13 in one ear only has the advantage of simplifying molds and molding procedure; and it also has the advantage that the rack is much less likely to become accidentally disassembled, because the hanger has to be swung to an abnormal position before it can be removed. It cannot be removed while in its hanging position of Fig. 3 because the clearances at C are not sufficient to allow the lefthand pin 11 to be moved to the top of slot 13 without the lefthand edge of the dependent hanger striking the lower inner edge of the lefthand bracket 10. But with the hanger in its upper vertical or near vertical position and with the right hand pin 11 in the outer end of slot 12, it will be noted that the vertical distance from that pin to the curved upper edge of the bracket is considerably less than the full vertical dimension of the bracket. Also it will be noted that the distance between the pins and the extreme head end of the hanger is less than the full vertical dimension of the bracket so that the left hand edge of the head end does not strike the lower inner edge of the left hand bracket as the left side of the hanger is moved up.

Figs. 4 and 5 diagrammatically illustrate the principles involved in the foregoing. The line at 10a represents the effective upper edge of the right hand bracket above the right hand pin 11 when that pin is at the outer end of its slot 12. That line is lower than the extreme upper edge of the bracket and of the slot 13, due to the curved upper-and-outer edge face 10b of the brackets. As shown in Fig. 4, the left hand edge of hanger 20 will strike the lower inner edge of left hand bracket 10 before left hand pin 11 reaches the upper end of slot 13. But as shown in Fig. 5, when the hanger is thrown to its upper vertical or near vertical position, the lower left hand corner 22a of the bracket head 22 will clear the inner face of left hand bracket 10, allowing the left side of the hanger, and its pin, to be lifted clear of left hand bracket 10 and its slot 13.

As shown in the drawing, slots 12 and 13 are shown as grooves which extend in depth from the inner faces of ears 10 only part way through the thickness of those ears. The depth extent however is immaterial and may be such as to extend clear through the thicknesses of the ears if desired.

We claim:

1. A rack of the character described, comprising the combination of a one-piece bracket and a one-piece hanger supported thereon, the bracket comprising an elongate base member adapted to be secured with its rear face against an upright surface, and two forwardly projecting ears at the ends of the base member and lying in substantially vertical planes, the hanger comprising a frame and cross-bars in grid formation, the frame having a transverse head member at one end and a pair of pins projecting outwardly from the side edges of the frame at a distance removed from the extreme head end of the frame, the bracket ears having horizontally extending slots in their inner faces which oppose each other and the bracket base having a horizontally extending groove in its forward face at about the level of the ear slots, said groove adapted to take the extreme head end of the hanger when the latter is in a substantially horizontal position, said ear slots taking the two hanger pins and being of such horizontal extent as to allow the hanger to be pulled out to disengage its head end from the bracket groove and thus to allow the hanger to be swung downwardly on its pins, and a vertical slot in at least one of the bracket ears adapted to pass at least one of the hanger pins upwardly from a horizontal ear slot when the hanger is disengaged from the bracket groove.
2. A rack of the character described, comprising the combination of a one-piece bracket and a one-piece hanger supported thereon, the bracket comprising an elongate base member adapted to be secured with its rear face against an upright surface, and two forwardly projecting ears at the ends of the base member and lying in substantially vertical planes, the hanger comprising a frame and cross-bars in grid formation, the frame having a transverse head member at one end and a pair of pins projecting outwardly from the side edges of the frame at a distance removed from the extreme head end of the frame, the bracket ears having horizontally extending slots in their inner faces which oppose each other and the bracket base having a horizontally extending groove in its forward face at about the level of the ear slots, said groove adapted to take the extreme head end of the hanger when the latter is in a substantially horizontal position, said ear slots taking the two hanger pins and being of such horizontal extent as to allow the hanger to be pulled out to disengage its head end from the bracket groove and thus to allow the hanger to be swung downwardly on its pins, and a vertical slot in one only of the bracket ears adapted to pass one of the hanger pins upwardly from a horizontal ear slot when the hanger is disengaged from the bracket groove, the other pin fitting its associated ear slot loosely and the transverse dimension of the head end of the hanger being less than the distance between the two opposed faces of the ears, to allow swinging movement of the hanger between the two ears as the one hanger pin is moved upwardly in its associated vertical slot.
3. A rack of the character described, comprising the combination of a bracket and a hanger supported thereon, the bracket comprising an elongate base member adapted to be secured with its rear face against an upright surface, and two forwardly projecting ears at the ends of the base member and lying in substantially vertical planes, the hanger comprising a flat frame having a transverse head member at one end and a pair

of pins projecting outwardly from the side edges of the frame at a distance removed from the extreme head end of the frame, the bracket ears having horizontally extending slots in their inner faces which oppose each other and the bracket base having a horizontally extending and downwardly facing shoulder behind its forward face at about the level of the ear slots, the head end of the hanger frame being adapted to lie under said shoulder when the hanger frame is in a substantially horizontal position, said ear slots taking the two hanger pins and being of such horizontal extent as to allow the hanger to be pulled out forwardly to disengage its head end from the bracket shoulder and thus to allow the hanger to be swung downwardly on its pins, and a vertically extending slot in at least one of the bracket ears adapted to pass at least one of the hanger pins upwardly from a point near the forward end of a horizontal ear slot to the upper edge of that ear slot, said vertical slot being inclined from a point near the forward end of the horizontal slot inwardly toward the front face of the bracket.

4. A rack of the character described, comprising the combination of a bracket and a hanger supported thereon, the bracket comprising an elongate base member adapted to be secured with its rear face against an upright surface, and two forwardly projecting ears at the ends of the base member and lying in substantially vertical planes, the hanger comprising a flat frame having a transverse head member at one end and a pair of pins projecting outwardly from the side edges of the frame at a distance removed from the extreme head end of the frame, the bracket ears having horizontally extending slots in their inner faces which oppose each other and the bracket base having a horizontally extending and downwardly facing shoulder behind its forward face at about the level of the ear slots, the head end of the hanger frame being adapted to lie under said shoulder when the hanger frame is in a substantially horizontal position, said ear slots taking the two hanger pins and being of such horizontal extent as to allow the hanger to be pulled out forwardly to disengage its head end from the bracket shoulder and thus to allow the hanger to be swung downwardly on its pins, and a vertically extending slot in one only of the bracket ears, said slot extending diagonally upwardly from a point near the outer end of the corresponding horizontal slot and inclining inwardly toward the front face of the bracket, said inclined vertical slot adapted to pass the corre-

sponding one of the hanger pins upwardly from the corresponding horizontal slot to substantially the extreme upper edge of said bracket, the other of said brackets having a downwardly and forwardly sloping top-and-front edge so that the vertical distance between the outer end of the horizontal slot and the upper edge of said bracket is less than the maximum vertical height of the first mentioned bracket.

5. A rack of the character described, comprising the combination of a bracket and a hanger supported thereon, the bracket comprising an elongate base member adapted to be secured with its rear face against an upright surface, and two forwardly projecting ears at the ends of the base member and lying in substantially vertical planes, the hanger comprising a flat frame having a transverse head member at one end and a pair of pins projecting outwardly from the side edges of the frame at a distance removed from the extreme head end of the frame, the bracket ears having horizontally extending slots in their inner faces which oppose each other and the bracket base having a horizontally extending and downwardly facing shoulder behind its forward face at about the level of the ear slots, the head end of the hanger frame being adapted to lie under said shoulder when the hanger frame is in a substantially horizontal position, said ear slots taking the two hanger pins and being of such horizontal extent as to allow the hanger to be pulled out forwardly to disengage its head end from the bracket shoulder and thus to allow the hanger to be swung downwardly on its pins, and
- 15 a vertically extending slot in one only of the bracket ears, said slot extending diagonally upwardly from a point near the outer end of the corresponding horizontal slot and inclining inwardly toward the front face of the bracket, said
- 20 inclined vertical slot adapted to pass the corresponding one of the hanger pins upwardly from the corresponding horizontal slot to substantially the extreme upper edge of said bracket, the other of said brackets having a downwardly and forwardly sloping top-and-front edge so that the vertical distance between the outer end of the horizontal slot and the upper edge of said bracket is less than the maximum vertical height of the first mentioned bracket, and the distance between the hanger pins and the extreme head end of the hanger being less than the maximum vertical height of the bracket ears.
